UNITED STATES PATENT OFFICE.

GEORGE S. SHEFFIELD, OF THREE RIVERS, MICHIGAN.

VEHICLE-WHEEL.

SPECIFICATION forming part of Letters Patent No. 279,449, dated June 12, 1883.

Application filed March 9, 1883. (No model.)

To all whom it may concern:

Be it known that I, GEORGE S. SHEFFIELD, a citizen of the United States, residing at Three Rivers, county of St. Joseph, State of Michigan, 5 have invented a new and useful Wheel, of which the following is a specification.

My invention relates to that class of wheels which are provided with detachably-connected spokes.

10 It has for its object an improved construction, the utility of which is set forth in the following description.

In the drawings forming a part of this specification, Figure 1 is a side elevation with portions broken away; Fig. 2, a section on line 1 1 in Fig. 1; Fig. 3, a portion of the hub in perspective; Fig. 4, a perspective view of a portion of the wheel exposed by the removal of a portion of the rim traced by line 7 8 in Fig. 1; 20 and Fig. 5 is a broken spoke in perspective.

The tubular portion S of the hub, which, in use, is secured on an axle, is provided with raised corrugations v v around its periphery, said corrugations having beveled sides, as in Figs. 1 and 25 3. The edges of the hub ends a of the spokes W rest against each other, said edges being beveled at the proper angle to admit of this, and to allow the spokes W to be located radially in the wheel, Fig. 1. These ends a of the 30 spokes terminate in double-beveled points r, adapted to fit into and fill the beveled corrugations v v, which detachably locks the spokes with the hub. By this means the ends of the spokes engaging the hub have an increased 35 bearing-surface against the hub—that is, the spokes of the lower half of the wheel all present a rigid resistance to the pressure on the wheel-rim, owing to the beveled sides of the points r resting or pressing against the beveled sides of the corrugations v v, Fig. 1. With the hub proper, S, and the spokes thus 40 related to it, I combine improved means for preventing lateral displacement of the spokes, consisting of peculiarly-constructed disks B C, 45 located on each side of the hub ends a of the spokes.

Disk B may be cast integral with the tubular portion of the hub, Fig. 2, and disk C detachably placed over the other end. These 50 disks are made with a depression in the center, and with a circular depression, f, between

said center depression and the periphery, thus forming ribs or bearing-surfaces d' e for resting against the spokes. In Fig. 1 the disk C is broken away, showing the construction and 55 relation of parts. The thickness of the hub ends a and points r of the spokes should be a little less than the length of the corrugations v v. Thus when the disks B C are secured together by bolts located in the holes between 60 the spokes and through the disks, Fig. 1, the ribs d' e are slightly embedded in the spokes. By this means the spokes are held secure by the transverse pressure of the circular ribs against the spokes, and in a bracing manner, 65 as the bearing of the ribs is against two different points between the ends of the spokes. Any shrinkage of the same may be compensated for by tightening the bolts. The points r are not marred nor broken, thus retaining their 70 full needed strength, and in the construction of the disks B C no portion of the inner face needs dressing, after having been cast, except the ribs d' e. The importance of having the two bearing-surfaces or ribs transversely across 75 the spokes at two different points between their ends may be more clearly explained as follows: The liability of the spokes to twist in their position, where they have so few rigid bearings or connections, could not be obviated 80 by a radial rib pressing against each of them at the radial center. A single transverse bearing-surface against the spokes would only partially obviate this liability, while with such a construction the single rib acts as a fulcrum to 85 the spoke when the wheel-rim springs or sways in use, and the spoke acts as a lever over said fulcrum, throwing its lower end laterally out of place. By the use of two transverse bearing-ribs both the twisting and leverage tendencies of the spoke are obviated, and, 90 in addition, the wheel-rim is less liable to spring or sway laterally. On the internal flange, L, of the wheel-rim are formed integral ribs e' e', thus making a recess between them, in which is 95 located the rim end of the spokes. A binding plate or cap, P, having a like recess, is placed over the spoke, and detachably secured by a bolt, C', passing through the flange, spoke, and binding-plate. This forms a simple and 100 conveniently-operated plan of securing this end of the spoke.

Having thus described my invention, what I claim is—

The combination of the tubular hub portion, the spokes, and the binding disks, each of said disks being provided with two flat circular ribs adapted to bear transversely against the sides of the spokes at the two different points shown, substantially as described.

In testimony of the foregoing I have hereunto subscribed my name in the presence of 10 two witnesses.

GEORGE S. SHEFFIELD.
